CONSTANT POTENTIAL SYSTEM

Walter van B. Roberts, Princeton, N. J., assignor
to Radio Corporation of America, a corporation
of Dealware

Application June 2, 1932, Serial No. 614,899

6 Claims. (Cl. 250—27)

1 My present invention relates to constant potential systems, and more particularly to a high frequency transmission network utilizing a pair of electron discharge tubes arranged in a constant potential system.

2 One of the main objects of my present invention is to provide a high frequency detecting or amplifying system wherein a pair of electron discharge tubes are arranged to have their input 10 circuits in push pull relation, and their anode circuits in series with a source of constant potential.

3 Another important object of the present invention is to provide a high frequency amplifying 15 arrangement which consists of a pair of electron discharge tubes having their input circuits arranged to receive energy to be amplified in opposite phase, and anode circuits connected in series with a source of constant potential, the control grids of the tubes being unequally biased whereby upper and lower amplification limiting points 20 are secured.

4 Another object of the present invention is to provide a detector for use between a radio frequency amplifier and a low frequency amplifier, the detector comprising a pair of electron discharge tubes having their control electrodes equally biased, and having their input circuits arranged to receive energy from the preceding 25 amplifier in opposite phase, the anode circuits of the detector tubes being arranged in series whereby the detector stage is capable of handling relatively high radio frequency input voltage, and additionally results in a minimization of the fundamental radio frequency component of the 30 energy detected.

5 Still other objects of the present invention are to provide a high frequency transmission network which includes a pair of electron discharge tubes 40 whose input circuits are arranged to receive energy to be transmitted in opposite phase, and means for biasing the grids of the two tubes in predetermined manner so as to operate the network as a detector or an amplifier, the anode circuits of the two tubes being arranged in series 45 relation.

6 And still further objects of the present invention are to improve generally the simplicity and efficiency of high frequency transmission networks, and to particularly provide a network which is not only reliable in operation, but capable 50 of utilization as a detector or an amplifier.

7 The novel features which I believe to be characteristic of my invention are set forth in particularity in the appended claims, the invention 55

itself, however, as to both its organization and method of operation will best be understood by reference to the following description taken in connection with the drawing in which I have indicated diagrammatically one circuit organization whereby my invention may be carried into effect. 5

8 In the drawing,

9 Fig. 1 diagrammatically shows a radio receiving system embodying the present invention, 10

10 Fig. 2 graphically illustrates the operation of the present invention.

11 Referring now to the accompanying drawing, and particularly Fig. 1, there is shown in the latter a network comprising electron discharge 15 tubes 1 and 2. The input electrodes, the cathode and control grid, of tube 1 are coupled to a tunable oscillation circuit by means of an inductance coil 3, the grid circuit of tube 1 including an adjustable negative bias source C'. 20 The input electrodes of tube 2 are coupled to the same tunable oscillation circuit including condenser 4 by means of coil 6, it being noted that an adjustable grid biasing source C is connected between the cathode and grid of tube 2. 25

12 The anode of tube 1 is connected to the positive terminal of a source B of anode potential, the anode of tube 2 being connected to the cathode of tube 1, and the negative terminal of the source B being connected to the cathode of tube 2 through a resistor 8. The source of energy for the tuned circuits of tubes 1 and 2 comprises a network 9 which may be a multi-stage radio frequency amplifier having a tunable input circuit including a variable condenser 10. Of course, the 30 radio frequency amplifier 9 may comprise one or more stages of radio frequency amplification, each of which stages has a tunable input circuit, and therefore it should be clearly understood that the tunable input circuit including the variable condenser 10 conventionally represents such one or more tuned radio frequency input 35 circuits. For simultaneous and similar tuning of the condensers 10 and 4, a mechanical uni-control 11, shown in dotted lines, may be utilized. 40 A coil 12 is arranged to couple the output of the amplifier 9 to the input circuit of tube 1, while a coil 13 is arranged to couple the amplifier output to the input circuit of tube 2. It will be seen from the diagram that the energies supplied to 45 tubes 1 and 2 are in phase opposition.

13 Any desired type of source of signal energy may be coupled, as at M, to the tunable input circuit of the amplifier 9. The source of signal energy may comprise the usual grounded antenna cir- 55

cuit, a loop antenna, or even a radio frequency transmission line. The terminal of resistor 8 which is connected to the negative side of source B is coupled to the grid of a succeeding electron discharge tube 20 through a coupling condenser 21, the cathode of tube 20 being connected to the opposite side of resistor 8. The resistor 8 is shunted by a fixed condenser 22. A potential source B' is arranged in the output circuit of tube 10 20 in order to provide proper positive potential for the anode of tube 20, and between the grid and cathode of tube 20 is arranged a series path which includes a bias resistor 23 in series with a source of negative grid bias potential 24. Any 15 well known type of utilization means may be coupled to the output circuit of tube 20, it being understood by those skilled in the art that such a utilization means may comprise a loud speaker, headphones, or any other desired type of loud speaker.

The operation of the present invention will now be described, particular reference being had to Fig. 2 which graphically demonstrates the mode of operation of the present invention. Fig. 2 25 shows how the plate current flowing in the common output circuit of tubes 1 and 2, which plate current is designated as i_B , varies with instantaneous values of voltage impressed upon the input circuits of tubes 1 and 2, such voltage being 30 represented by the symbol e .

It can be shown that $i_B=0$, when

$$e = \pm \left(\frac{B - \mu C}{\mu} \right)$$

35 where B = voltage of battery B, C = voltage of battery C and μ = amplification constant of the tubes. Let it be assumed that the signal impressed upon the input circuit of tubes 1 and 2 is a 500 cycle tone, and e is adjusted to be at least as great as 40 the cut-off value given above, then the current i_B will fall to zero at each half cycle of the tone, rising to the maximum value shown in Fig. 2 between each fall. This creates a 1,000 cycle tone in the reproducer coupled to the output of tube 45 20. Thus, in Fig. 2, point D shows the point which is used for detector operation, in this case the bias on the grids of tubes 1 and 2 being equal. That is $ec = ec'$. With the circuit adjusted in this manner the network including tubes 1 and 2 50 operates as a power detector, and suppresses the fundamental radio frequency component.

The virtue of the arrangement is that when operated at full output, no interfering signal or static crash, can cause any more variation in current through resistor 8 than the signal does. In order to make the resulting loudness or deafening effect in the reproducer as small as possible, it is advisable to shunt the resistor 8 with as large a capacity as is possible without too greatly weakening the signals. This capacity 22 prevents extremely sudden changes of current in the reproducer even if an extremely sudden voltage is applied to the tubes 1 and 2 along with the desired signal. An elaborate low pass filter would be 65 preferable to this condenser.

In case a signal is desired without the detecting and frequency doubling effect discussed heretofore, unequal bias may be put on the tubes 1 and 2, so that the operating point lies on the straightest part of the characteristic, and represented in 70 Fig. 2 by the symbol A. When the grid biases of tubes 1 and 2 are adjusted in this manner, then the network including tubes 1 and 2 operates as an amplifier; that is ec is not equal to ec' . If the 75 desired signal varies the current from nearly zero

to nearly maximum, the static to signal current ratio will not greatly exceed unity. It will also be observed that when the tubes 1 and 2 are biased to point A of Fig. 2, then there exists an upper and lower limiting action on the output current. 5

Of course, when the network including tubes 1 and 2 operates as an amplifier of high frequency energy, then a succeeding tube such as 20 must be adjusted to operate as a detector, and the detector tube would preferably be followed by an audio 10 frequency amplifier. It should also be observed that when the network including tubes 1 and 2 operates as a power detector, it is capable of handling input voltages up to large magnitudes such as for example 40 volts, and is capable of 15 delivering an output of the same order of magnitude.

While I have indicated and described several systems for carrying my invention into effect, it will be apparent to one skilled in the art that my 20 invention is by no means limited to the particular organizations shown and described, but that many modifications may be made without departing from the scope of my invention as set forth in the appended claims. 25

What I claim is:

1. In combination in a high frequency transmission network, a pair of electron discharge tubes having their space discharge paths connected in series and being provided with a common output circuit, a source of constant potential arranged in said common output circuit, the input circuits of said tubes being arranged to have energy to be transmitted, impressed upon them in opposite phase, and means in each input circuit of each tube for negatively biasing the grid of each tube in unequal manner. 35

2. In combination in a high frequency transmission network, a pair of series connected electron discharge tubes provided with a common output circuit, a source of constant potential arranged in said common output circuit, the input circuits of said tubes being arranged to have energy to be transmitted, impressed upon them in opposite phase, means for unequally, and negatively, biasing the grids of said tubes, a resistor in said common output circuit, and an electron discharge tube having its input electrodes directly coupled across said resistor. 40

3. A circuit for high level detection with suppression of radio frequency fundamental and exhibiting sharply defined saturation above a predetermined level, comprising a pair of series connected electron discharge tubes provided with a common output circuit, a source of constant potential arranged in said common output circuit, the input circuits of said tubes being arranged to have energy to be transmitted, impressed upon them in opposite phase, and means in each input circuit of each tube for biasing the grid of each tube in a predetermined manner with equal biases. 50

4. A circuit for linear amplification with sharply defined saturation above a predetermined level comprising a pair of series connected electron discharge tubes provided with a common output circuit, a source of constant potential arranged in said common output circuit, the input circuits of said tubes being arranged to have energy to be transmitted, impressed upon them in opposite phase, and means in each input circuit of each tube for biasing the grid of each tube in a predetermined manner with unequal bias. 65

5. In a radio receiver, a radio frequency amplifier adapted to deliver radio frequency voltages of large magnitudes, a power detector network 70

capable of delivering an output of the same order of magnitude, said network comprising a pair of tubes having the grids thereof connected to the output circuit of said amplifier, said connection being such that the radio frequency voltages applied to the grids are in phase opposition, means for normally maintaining said grids negatively biased, a source of constant potential in the anode circuit of one of the tubes, the anode to cathode path of the other tube being connected in series with said potential source and with the anode to cathode path of the said one tube.

6. In a radio receiver, a tunable, multi-stage radio frequency amplifier adapted to deliver radio frequency voltages of large magnitudes of the

order of 40 volts, a power detector network capable of delivering an output of the same order of magnitude, said network comprising a pair of tubes having the grids thereof connected to the output circuit of said amplifier, said connection 5 being such that the radio frequency voltages applied to the grids are in phase opposition, means for normally maintaining said grids negatively biased, a source of constant potential in the anode circuit of one of the tubes, the anode to cathode 10 path of the other tube being connected in series with said potential source and with the anode to cathode path of said one tube.
